UNITED STATES PATENT OFFICE.

LEO HEWETTE WHELAN, OF YOUNGSTOWN, OHIO.

TIMER FOR ENGINES.

1,306,791.

Specification of Letters Patent. Patented June 17, 1919.

Application filed January 3, 1919. Serial No. 269,406.

To all whom it may concern:

Be it known that I, LEO H. WHELAN, a citizen of the United States, residing at Youngstown, in the county of Mahoning 5 and State of Ohio, have invented certain new and useful Improvements in Timers for Engines, of which the following is a specification.

This invention relates to internal combustion engines, and especially to the ignition systems thereof; and the object of the same is to produce an improved timer for use particularly on Ford cars.

One object is to increase the accessibility 10 of parts so that the repairs and adjustments can be readily made.

Other objects will appear in the following specification and claims. In the drawings:—

Figure 1 is an elevation of a portion of a 20 Ford car showing the position of the timer.

Fig. 2 is an enlarged front elevation of the timer itself.

Fig. 3 is a section on the line 3—3 of Fig. 2.

Fig. 4 is an elevation from the inside of 25 the cap of the timer showing the fiber cup.

As is well known, the timer for an ordinary internal combustion engine comprises a rotating element or "brush" mounted on 30 an appropriate shaft which is the front end of the cam shaft in the Ford machine; and a relatively fixed although slightly adjustable element bearing several "points" with which the brush makes contact successively 35 and from which lead wires to the spark plugs. The present invention contemplates no change in the rotating element or brush and therefore the same is not illustrated.

The timer herein comprises a hollow element or shell 1 whose inner portion constitutes a substantially cylindrical body 2 and whose outer portion is dome-shaped or nearly conical, being open at 3 to receive the nose 4 of an elbow 5 which is held removably 40 in said opening by a spring 6 indicated in Fig. 1. Projecting radially from or secured to one side of the cap is an ear 7 to which is attached a rod which leads through suitable 45 connections to a hand lever within reach of the driver, whereby the entire shell and its contents may be adjusted around its axis to advance or retard the spark as well understood. I have not thought it necessary to show the wires, except the cable 8 in Fig. 1, 50 but it will be clear that this cable leads in through the elbow of Fig. 3 and turns down-

ward through its nose into the interior of the cap 1, and the wall of the latter is provided with four inside grooves 9 for the four wires of this cable. 60

Inside the cap is placed a fiber cup 10 which is shown in section in Fig. 3 but omitted in Fig. 4, and this cup has four holes 19 at proper points to register with the grooves 9 so that the several wires of the cable may 65 pass therethrough. Otherwise the cup prevents the escape of grease or whatever the packing used within the timer and through the elbow or through the space between the nose and the wall of the opening 3. Within 70 in the cylindrical body 2 of the timer is placed a fiber ring 12 indicated in black in Fig. 4 and provided with notches at four points for the plates 13 constituting the heads of the points, which plates are curved 75 slightly as shown in white in Fig. 4 and have their faces struck on the same curve as the inner face of the fiber ring 12. The stem 14 of each point leads radially outward through the fiber ring, thence through an 80 insulating bushing 15 which is seated in a hole in the body 2, and finally receives a nut 16 at its outer extremity. Each wire from the cable is led down one of the grooves 9, through one of the holes 19, and is connected 85 with the stem of the point just beneath its head or plate 13; whereas appropriate connection is made from the single wire to the brush (not shown) which rotates within the cylindrical body portion 2 and makes 90 contact with the several plates 13.

The brush being mounted on the forward end of the shaft, it is obvious that in order to gain access to the interior of this timer, it is only necessary to remove or turn aside the 95 spring 6 and withdraw the elbow 5 which slips along the cable 8 so that its nose 4 comes out of the opening 3 of the cap 1. There is now nothing holding the shell in place, and it can be readily removed, especially if the 100 rod is unhooked from the ear 7 or permitted to flex. Assuming that the shell and its contents are drawn away from the brush, the shell can be turned aside to give access to the interior for cleaning or repair. Also as soon 105 as the shell and its contents are removed, the brush and its parts are exposed for cleaning and repair. After having received proper attention, the parts are restored by a reversal of this operation and without the necessity for tools. Thus it will be seen that I 110 have produced a timer which is extremely

simple and efficient. The primary objects are those first set forth above.

The foregoing description and the drawings have reference to what may be considered the preferred or approved form of my invention. It is to be understood that I may make such changes in construction and arrangement and combination of parts, materials, dimensions et cetera, as may prove expedient and fall within the scope of the appended claims.

Having thus fully described my invention, what I claim as new and desire to secure by Letters Patent is:—

1. In a timer, the combination with a shell having a cylindrical body and a conical cap with an opening at its apex, the inner wall of said cap being grooved toward the opening and the body having holes opposite said grooves, a series of points whose stems are mounted through said holes and insulated from the body, and a fiber cup within said shell and having holes opposite said grooves; of a tubular member mounted rotatably in said opening and serving as a conduit for the cable and the grooves and holes as passage ways for the respective wires thereof, for the purpose set forth.
2. In a timer, the combination with a shell having a cylindrical body and a conical cap

with an opening at its apex, the inner wall of said cap being grooved toward the opening and the body having holes opposite said grooves, a series of points whose stems are mounted through said holes and insulated from the body, and a fiber cup within said shell and having holes opposite said grooves; of an elbow whereof one arm is mounted rotatably in said opening in the cap, the elbow serving as a conduit for the cable and the grooves and holes as passage ways for the respective wires thereof, and a spring bearing normally on the angle of the elbow, for the purpose set forth.

3. In a timer, the combination with an elbow for the cable, and a spring bearing normally against its angle; of a shell having a cylindrical body and a conical cap with an opening receiving one arm of the elbow, the same being borne thereinto by the spring, a fiber cup within the cap of said shell and pierced with openings for the wires of said cable, and a plurality of points within the body of said shell and insulated therefrom.

In testimony whereof I affix my signature in presence of two witnesses.

LEO HEWETTE WHELAN.
